DISPENSING CONTAINER WITH SIFTER TOP

George C. Erb, deceased, late of Flushing, N. Y.,
by Annie B. Erb, executrix, Flushing, N. Y., as-
signor to American Can Company, New York,
N. Y., a corporation of New Jersey

Application November 10, 1949, Serial No. 126,642

4 Claims. (Cl. 222—548)

1

The present invention relates to dispensing containers, and more particularly to a dredging container having a distinctive and novel sifter top construction.

An object of the present invention is to provide a sifter top container wherein the rotatable or slidable closure member is held in place by a shoulder formed by reshaping or collapsing the countersink wall of the stationary end member.

Another object of the invention is to provide a resilient connection between the slidable closure member and the stationary end member of a sifter container to overcome any tendency of the container to leak because of dimensional variations incurred in the manufacture or assembling of these parts.

A further object of the invention is to provide a dispensing container wherein the cylindrical depending wall of an inverted cup-shaped, rotatable closure member provides a gripping surface to facilitate rotation of the closure, the lower edge of the depending wall being utilized to secure the closure member to the container.

Yet another object is to provide a dredging container wherein a slidable closure member is held in contact with a stationary boss under spring tension to insure a tight, sift-proof engagement between the two.

A still further object is to provide a dispensing container of pleasing appearance, wherein an inverted cup-shaped closure member having a smooth, flat sifter surface elevated above the level of the end seam is adapted to nest within the countersunk bottom of a similar container to facilitate stacking.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a container embodying the instant invention;

Fig. 2 is an enlarged sectional view of a portion of the upper end of the container shown in Fig. 1, the view showing a closure member in place on the container prior to assembly therewith;

Fig. 3 is an enlarged sectional view similar to Fig. 2 showing the closure member assembled on

2

the container, and showing in dotted lines the lower portion of another container in stacked relation; and

Fig. 4 is a sectional view similar to Fig. 3 illustrating a modified form of the invention.

As a preferred or exemplary embodiment of the instant invention, Fig. 1 illustrates a container formed with a tubular body 10, preferably cylindrical as shown. A bottom end member 11 is attached to the lower end of the body 10 in any suitable manner.

At the upper end of the body 10, a top end member 12 is secured thereto, preferably although not necessarily, by means of a double seam 13. As shown in Fig. 2, the end member 12 is originally formed with a straight countersink wall 14 which constitutes the inner layer of and extends downwardly from the top of the double seam 13 and is connected by a curved wall section 15 with an upwardly extending wall portion 16.

The wall portion 16 in turn merges into a flat panel section 17 to form a dome or boss 20 which is raised substantially above the level of the top of the double seam 13 (Fig. 3). The flat panel 17 of the boss 20 is provided with suitable dispensing or sifter openings 22, through which the contents of the container may be removed when the container is inverted and shaken.

The size and disposition of the openings 22 will be determined by the nature of the container contents. In some cases it may be desirable to provide an opening large enough to permit filling of the container or the insertion of a tablespoon or other utensil for removal of a measured amount of the contents.

In order to close the openings 22 when desired, a cup-shaped outer slidable or rotatable closure member 25 is provided. The closure member 25 is formed with a flat panel 26 having therein openings 27 which are aligned to register with the openings 22 in the end panel 17. Depending from the outer edge of the closure panel 26 is a substantially vertical cylindrical wall 28 provided with knurls or corrugations 29 to facilitate gripping when the closure is to be rotated. The lower edge of the wall 28 is preferably bent outwardly and upwardly to form an open curl 30, as shown in Fig. 2.

To secure the closure member 25 tightly to the other parts of the container, it is positioned upon

the top end member 12 so that the closure panel 26 engages the end panel 17 while the curl 30 preferably is disposed just above the curved section 15 of the end member 12 (see Fig. 2). When the parts are so positioned, the straight countersink wall 14 which forms the inner layer of the end seam 13, is collapsed or reshaped to form an inwardly extending shoulder 31 which projects over and engages against the closure curl 30, thus securing the closure 25 to the end member 12. During this collapsing operation, the end member 12 and the closure 25 are both moved upwardly with respect to the end seam 13. Thus, the internal capacity of the container is increased. This collapsing or upsetting operation is described in detail in applicant's co-pending application Serial Number 126,641, filed November 10, 1949, and is done before the bottom end 11 is secured onto the body 10 to permit the insertion of an inside collapsing or upsetting mandrel or post.

As can be seen in Fig. 3, the shoulder 31 comprises a substantially horizontal wall 32, which extends inwardly from the top of the double seam 13, and an inclined, reversely bent wall portion 33. The reversely bent wall 33 engages against the curl 30 of the closure 25 and deforms the curl to some extent, thus providing a resilient connection between the closure 25 and the end member 12. This resilient connection permits considerable tolerance in the dimensions of the assembled parts and in the degree of collapse of the countersink wall 14.

The main deformation of the open curl 30 by the shoulder 31 occurs in its upper or terminal portion and is both inward and downward, as can be seen by comparing Figs. 2 and 3. The downward component of the pressure resulting from this deformation maintains the closure 25 under tension tightly against the boss 29, thus creating a substantially leakproof but relatively movable engagement between these two parts.

When the rotary sliding closure member 25 is in the position shown in Fig. 3, the openings 22 and 27 are in registry and the contents of the container may be dispensed through them. To close the container, the vertical closure wall 28, which extends upwardly a considerable distance above the end seam 13 is gripped by the consumer and the closure is rotated to move the openings out of registry. The knurlings or corrugations 29 facilitate rotation of the closure member.

As can be seen in Fig. 3, the container of the instant invention is adapted for stacking. The broad flat-topped closure member 25 nests within the countersunk bottom end member 11 of a similar container (illustrated in dot and dash lines), thus making it possible to build a non-slipping column of superposed containers.

Figure 4 illustrates one of several possible modifications of the invention. The container illustrated in this figure is similar to that in Figs. 1, 2, and 3. The lower edge portion of the depending wall 28, however, instead of being curled, is formed into an outwardly extending substantially straight flange 35. The inclined wall 32 of the shoulder 31 engages against the outer portion of the flange 35 and exerts a downward pressure thereagainst which holds the closure 25 under tension against the boss 29. The flange 35 is preferably deformed downwardly by the wall 33 to maintain the desired spring tension.

The principles of the instant invention may obviously be embodied in other modified forms of

dispensing containers. A suggested example would be a reciprocating type of dredging container having a rectangular sliding closure member.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

What is claimed is:

1. A dispensing container comprising a body, an end member secured to said body in an up-standing end seam the inner layer of said seam being a portion of said end member, a shoulder formed in only said inner layer of the seam and extending inwardly from said seam, a panel in said end member having a dispensing opening formed therein, a closure member having a perforate inner portion disposed in close sliding contact on said end member panel to cover and uncover said dispensing opening, and a marginal portion of said closure member projecting outwardly toward said end seam and engaging under said shoulder to retain said closure in place and in close sliding contact upon said end member.
2. A dispensing container comprising a body, an end member secured to said body in an up-standing end seam the inner layer of said seam being a portion of said end member, a shoulder formed in only said inner layer of the seam and extending inwardly from said seam, a panel in said end member having a dispensing opening formed therein, a closure member having a perforate inner portion disposed in close sliding contact on said end member panel to cover and uncover said dispensing opening, and a peripheral curl on said closure member protecting outwardly toward said end seam and engaging under said shoulder to retain said closure in place and in close sliding contact upon said end member.
3. A dispensing container comprising a body, an end member secured to said body in an up-standing end seam the inner layer of said seam being a portion of said end member, said inner layer only of said end seam having a shoulder formed therein extending inwardly from the upper portion of the seam and thence downwardly and outwardly in an inclined wall, a panel in said end member having a dispensing opening formed therein, a closure member having a perforate inner portion disposed in close sliding contact on said end member panel to cover and uncover said dispensing opening, and a marginal portion of said closure member projecting outwardly toward said end seam and engaging said inclined wall of the shoulder to retain said closure in place and in close sliding contact upon said end member.
4. A dispensing container comprising a body, an end member secured to said body in an up-standing double seam the inner layer of said seam being a portion of said end member, said inner layer only of said double seam having a shoulder formed therein extending inwardly from the upper portion of the seam and thence downwardly and outwardly in an inclined wall, a flat panel in said end member raised above the top of said seam and having a dispensing opening formed therein, a closure member having a

flat perforate inner portion disposed in close sliding contact on said flat end member panel to cover and uncover said dispensing opening, and a marginal portion of said closure member projecting downwardly and outwardly toward said double seam and engaging said inclined wall of the shoulder to retain said closure in place and in close sliding contact upon said end member.

ANNIE B. ERB, 10
Executrix of the estate of George C. Erb, deceased.
